UNITED STATES PATENT OFFICE.

GEORGE ERLINGER, OF MILWAUKEE, WISCONSIN, ASSIGNOR OF ONE-HALF TO ALBERT O. TROSTEL AND ONE-TWENTIETH TO ADRIAN A. WEDEMEYER, BOTH OF MILWAUKEE, WISCONSIN.

EXPLOSIVE-TURBINE.

1,166,117.

Specification of Letters Patent. Patented Dec. 28, 1915.

Application filed February 5, 1914. Serial No. 816,685.

To all whom it may concern:

Be it known that I, GEORGE ERLINGER, a citizen of the United States, and a resident of the city of Milwaukee, county of Milwaukee, State of Wisconsin, have invented certain new and useful Improvements in Explosive-Turbines, of which the following is a specification.

My invention relates to improvements in gas turbines, and refers more particularly to that type of explosive turbine which operates by virtue of a charge of live gas exploding and directly impinging upon the turbine wheel.

Among the salient objects of the invention are to provide a self-contained gas turbine which utilizes the full explosive force of a mixture of gas and air exploded in a separate chamber adjacent to the propeller wheel; to provide, in an explosive gas turbine of the class described, a turbine member composed of a series of propeller wheels through which the exploded mixture passes successively, the wheels successively increasing in capacity as the exploded mixture passes from one to the other; to provide, in a gas turbine of the class described, a central propeller wheel with a double row of buckets or impeller blades upon which the exploded mixture impinges initially and then divides into a pair of substantially equal streams passing through a series of wheels on each side of the double central wheel, and successively increasing in size until two exhaust openings are reached at the ends of the turbine chamber; to provide, in a gas turbine of the class described, a construction which will admit of the use of one or a plurality of explosive chambers and pressure nozzles arranged around the periphery of the central impeller disk; to provide a construction in which the gases in passing from one wheel to another are held in engagement with each wheel during a comparatively small portion of a revolution, and then pass diagonally across the face of the turbine to the next impeller disk, the main direction of travel of the gases being substantially in the same general direction as the direction of rotation of the turbine; to provide, in a turbine of the class described, a detonating chamber which is arranged to receive an explosive mixture under compression, explode the latter while still under compression, keep the charge un-

der confinement until a high pressure has developed, and finally admit the exploded mixture to the turbine nozzle; to provide a construction in which the spent gases as they pass from the detonating chamber and through the turbine are followed by a scavenging charge of fresh air, the gases in their passage through the turbine tending to augment this effect by sucking the air following; to provide a construction in which the impelling gas consists of a series of separate and independent exploded mixtures separated by greater or less intervals, depending upon the amount of power demanded from the turbine, and independent of its speed of rotation; to provide a construction in which the power or speed of the turbine, or both, may be regulated, either by varying the richness or pressure of each individual charge, or by decreasing or increasing the number of charges or explosions per minute; to provide a construction in which the admission of gas, exhaustion of the latter and admission of the scavenging air are all accomplished by means of a single cylindrical, ported valve which oscillates or rotates continuously within the detonating chamber and forms the inner shell thereof, the valve being actuated by an independent motor on the exterior of the detonating chamber; to provide an improved gas turbine which will be both extremely simple in operation and economical in construction; and in general to provide an improved explosive turbine of the character referred to.

The invention consists in the matters hereinafter described, and more particularly pointed out in the claims appended at the end of this specification.

In the drawings.—Figure 1 represents my improved gas turbine and associated apparatus as a whole, the lower portion of the air receiver being broken away to reduce the size of the drawing; Fig. 2 is an elevation of the left-hand end of Fig. 1, the air tank not being shown; Fig. 3 is a partial cross section of Fig. 1, taken through one of the central turbine disks; Fig. 4 is a section taken along the line 4—4 of Fig. 3; Fig. 5 is a cross section of the detonating chamber and valve, and a portion of the periphery of the turbine casing; Fig. 5^a is a fragmentary section along the line 5^a of Fig. 3; Fig. 6 is a section along the line 6—6 of Fig. 5, the valve having been removed; 110

Fig. 6^a is a section through Fig. 6 along the line 6^a; Fig. 7 shows the rotary valve removed from the detonating chamber; Fig. 8 is an end elevation of Fig. 7; and Fig. 9 shows the details of the ignition mechanism.

Referring to the drawings, 1 represents an air receiver or tank, upon the upper side of which is mounted the turbine casing 2 and gasoline tank 3. The tank 1 is kept 10 fully charged with air under pressure by the air pumps 4, which, as shown in Fig. 2, are driven by the main turbine-shaft 6, upon the end of which is mounted a small pinion 7 operating the pistons of the air pumps 15 through suitable reduction gearing and crank connections. Although I have shown the air pumps as being driven from the shaft of the turbine itself in order to make the apparatus self-contained, any suitable 20 source of compressed air or externally-operated pump may be used to keep the tank 1 full of air under pressure. From the top of the tank 1 projects a pipe 8 which admits air under pressure through the valve 9 to the top of the gasoline tank 3, thus 25 maintaining pressure on the surface of the liquid, which is thus fed to the gasoline reservoir 10 under a considerable pressure.

The detonating chamber 11 is bolted to a 30 suitable gas-tight seat 12 on the side of the turbine casing, and cooling is effected by an annular water-jacket 13, which, when the chamber 11 is bolted to the seat 12, forms 35 a continuation of the main water-chamber 14 extending around the circumference of the main turbine-casing outside of the interior casings for the impeller wheels proper. Water is also circulated through subsidiary, 40 annular water-chambers 15, situated between each adjacent pair of turbine disks, and connected to the outer jacket by openings at the top and bottom of the casing. The entire turbine casing is split horizontally 45 to permit the ready insertion of the rotating element. The circulating pump for the cooling water is not illustrated in the drawings, but is connected to the pipe 16, the inlet to the lower part of the water 50 chamber also being omitted from the drawings.

Within the cylindrical detonating chamber 11 oscillates the valve 17, which 55 comprises a simple, hollow cylindrical casting having an exhaust port 18 and inlet port 19, leakage of gas being prevented by the two circumferential rings 20 and 21 located in grooves in the periphery of the valve. The back of the valve has an annular recess 22, 60 which communicates with the interior of the valve by a pair of equalizing ports 23. The purpose of this annular chamber 22 is to admit gas under pressure at the back of the valve, so that the latter will always be 65 forced inwardly toward the center of the

turbine, insuring a gas-tight joint between the inner end of the valve and the adjacent bearing face of the detonating chamber. The valve 17 is actuated through a shaft 12^a which projects through and has bearing in 70 a head 25 bolted to the outer end of the detonating chamber.

I have illustrated as a means of actuating the shaft 12^a a small air-motor designated as a whole 26, bolted to the side of the turbine casing, and driven by a supply of compressed air taken from the main tank 1 through the regulating valve 27. This air-motor may be of any ordinary type such as is used in pneumatic percussion devices 80 and exhausts into the end of the hollow turbine shaft through the pipe 26' and the loose fitting cylindrical cap 27'. This current of air in its passage through the shaft is of material assistance in cooling the 85 wheels. The shaft 12^a of the detonating valve is connected to the piston rod 28 of the air-motor by means of a slotted crank 29 engaged by the sliding crank pin 30 on the end of the piston rod. The rod 31 90 controlling the slide valve of the air-motor is pivotally connected to a link 32, the other end of which is attached to a small, subsidiary crank 33. It is obvious that if the valve 27 be opened, air under pressure will 95 reciprocate the piston 28, and the valve 17 will thus oscillate back and forth a definite angular amount controlled by the length of the stroke of the air-motor 26.

Air for scavenging purposes is admitted 100 from the tank 1 through the pipe 34^a to the detonating chamber by the radially-opening port 35, fuel being supplied through a similar port 36 in the same vertical plane as the port 35, but angularly spaced from the latter. At the proper angular point between and in the same vertical plane as the ports 35 and 36 is situated an orifice 37, which contains the end of the spark plug 38 screwed into the aperture from the outside of the detonating chamber. The apertures 35, 37 and 36 are arranged the proper distance from the head of the valve to be successively in register with the port 19 105 in the valve 17 as it oscillates within the detonating chamber. The high-pressure exploded mixture is admitted to the initial nozzle 39 through a port 40 in the inner end of the detonating chamber, the port 18 in the valve being properly located to register 110 with the admission port 40 at an appropriate point during the oscillation of the valve.

Tracing the passage of the gases through the turbine, it will be seen, by referring to Figs. 3 and 4, that the nozzle 39 impinges upon the main central turbine-disk at an angle suitable for utilizing the kinetic energy of the moving gas to the best advantage. The moving gas entering through the nozzle 39 engages both series of buckets 115 120 125 130

41 in the periphery of the central disk 42, which, together with the other impeller wheels, is keyed to the main shaft 6 of the turbine, the latter rotating upon ball bearings 43 mounted in the main casting of the turbine chamber at the ends and at two intermediate points. As the turbine-disk rotates in the direction of the arrow (see Fig. 3), the gas remains in the buckets until the latter reach the longitudinal passage 44 located at the outer edge of the impeller wheel 42 at a point rather less than ninety degrees in angular spacing from the entering nozzle 39. The gas entering this longitudinal passage 44 divides, half of it passing longitudinally in either direction to the next nozzle 45, shown dotted in Fig. 3, this nozzle being located approximately at an angle of ninety degrees from the first nozzle 39. It will be noticed that the gases in passing from the nozzle 39 to the nozzle 45 always retain a general direction of travel corresponding to the direction of rotation of the turbine, this being the case also as the gas progresses through the turbine, through succeeding nozzles and impeller wheels. The gases impinge upon the buckets of the wheels 46 through the nozzles 45, and are carried around to a second set of longitudinal openings similar to the openings 44, and situated at an angle of ninety degrees therefrom. These openings lead the now partially expanded gases to a pair of nozzles (not shown) associated with the wheels 47, which carry the partially spent gases to the final wheels 48, through the two longitudinal openings 49 at the bottom of the casing, which are connected to nozzles not shown. The finally exhausted gases pass out of the casing through a pair of pipes 50 communicating with openings at the periphery of the final wheels 48. It will be seen, from reference to Fig. 4, that the initial rows of buckets in the central impeller disk are the smallest of the series, the buckets successively increasing in size as the gases pass through the turbine and operate on succeeding wheels. It is understood, of course, that all of the impeller wheels are securely keyed to the shaft 6 and rotate at the same speed.

Ignition is effected by means of the vibrating spark coil 51 supplied with current from the battery 52, the high-tension current being conducted from the binding post 53 to the spark plug by means of a wire 54. The primary circuit of the coil 51 is made and broken by virtue of a breaker mechanism, of which a detail view is given in Fig. 9. Upon an extension of the head 25 of the detonating chamber is mounted a fiber block 55, which carries at the outside thereof a bent-up piece of strap metal 56, to which is secured the diagonal guide-member 57. The block 55 is further provided with a longi-

tudinally extending aperture within which slides the contact block 58, the lower portion of which is threaded to fit the adjusting screw 59. The latter is rotatably mounted in the block 55, and is suitably prevented from moving longitudinally therewith, so that when the screw 59 is turned by means of the knurled head 60, the block 58 will be moved longitudinally a definite amount. Attached to the block 58 is a pointer 61, the end of which is bent at right angles to register with a graduated scale 62 (see Fig. 9 and Fig. 1). This graduated scale comprises a length of spring metal attached at one end to the block 55, and the other end being bent over at a suitable angle to engage the milled collar 63 fixed to the screw 59; this is to insure against accidental false movements of the screw 59, owing to vibration or other causes. The insulated contact block 58 is connected through the metal of the screw 59 to the binding post 64, the base of which forms a bearing for a shouldered neck on the end of the adjusting screw 59, one side of the primary circuit of the induction coil being connected to the binding post 64 by a wire 65 the other terminal of the circuit being grounded on any convenient part of the metallic frame of the turbine in the usual manner. On the end of the shaft 12^a is adjustably secured a small arm 65^a, which carries firmly attached to its lower end a leaf spring 66, which is of such a length that when the shaft 12^a is oscillated, the end of the spring engages the cam block 57, and an intermediate contact piece 66^a mounted on the spring, engages the contact block 58 as the spring passes under the cam block 57. The latter is of such shape and length, and is located at such distance from the center of the shaft 12^a, that when the latter oscillates, the end of the spring 66 first engages the cam surface 67 of the cam block, and is then carried along the under side of the latter until the end of the spring passes beyond the point 68 and flies up into its original normal plane of oscillation. As previously stated, when passing along the under surface of the cam block, an intermediate portion of the spring makes contact with the block 58, and so energizes the spark coil 51 in an obvious manner. As the shaft oscillates in the reverse direction, the end of the spring 66, in its return movement, strikes the cam surface 69 of the cam block, is deflected above guide 57, and is thus prevented from making contact with the block 58. Consequently ignition is effected only during the oscillations of the shaft 12^a in one direction.

Describing the operation of the turbine, and assuming that the tank 1 has been previously charged with compressed air and that all of the controlling valves 70, 71, 72 and 9 have been opened, the valve 27 is

turned slightly, and the air-motor 26 starts to operate and oscillate the valve 17 back and forth. Assuming that the fuel port 36 is the first port that happens to be in register with the port 19 of the valve, air under pressure will be forced through the valve 71 and the pipe 74, and will meet a stream of gasoline spray in the mixing connection 75, between which and the gasoline reservoir 10 voir 10 the spray nozzle (not shown) is located. The explosive mixture will thus enter the chamber through the check valve 76 and the open ports until the pressure in the chamber is equal to the pressure in the tank, or until the ports close and the supply is thus shut off. While this is occurring, the piston of the air-motor has commenced its outward movement, the valve starts to rotate in the direction of the arrow 20 77 (see Fig. 6), and the port 19 passes out of register with the port 36, and shortly afterward uncovers the orifice 37 within which the spark plug 38 is located. At the proper moment (which can be regulated 25 by adjusting the milled screw-head 60), the arm 66 makes contact with the contact block 58 and grounds the latter, completing the circuit through the primary winding of the spark coil 51. Ignition then takes place. 30 While all the above has happened, the port 40 has been closed, but shortly after ignition has taken place, the valve 17, continuing its oscillation in the same direction, brings the port 18 in register with the port 35 40, which, as previously stated, admits the high-pressure exploded mixture to the initial nozzle of the turbine. The latter accordingly is at once put in motion, and the gases are carried away by the buckets in the 45 periphery of the impeller disks, which receive the direct impact of the explosion as the high-pressure gas is admitted through the port 40. The port 40 remains in communication with the detonating chamber for 50 a considerable length of time, in fact, long enough for the entire exploded charge to pass out of the nozzle. Just before the valve reaches its extreme limit of oscillation in the direction of the arrow 77, the port 19 comes 55 into register with the scavenging port 35, and air from the tank passes into the chamber through the pipe 34^a and check valve 78. This cleans out the remnants of the spent gases, the scavenging effect also being 60 augmented by the suction produced in the wake of the exploded gases passing out of the nozzle at high velocity, and being carried off by the buckets of the turbine. Independently of the last-named action, however, scavenging is effected expeditiously and completely by the air forced into the chamber through the port 35. Shortly after the port 35 has been opened, the valve reaches its extreme limit of movement in 65 the direction of the arrow 77, and as the

piston of the air-motor commences to move in the other direction, the valve also commences its reverse oscillation, and quickly closes the port 35. Since the port 40, however, is still open, the excess of pressure 70 in the valve chamber is dissipated through the nozzle, and owing to the suction effect previously referred to, the chamber is partially exhausted before the port 40 is closed. Continuing its oscillation in the direction 75 of the arrow 79, the valve, filled with comparatively rarefied air, as just described, again travels around to a point where the valve port 19 registers with the fuel-inlet port 36, and a fresh explosive charge is 80 admitted. Shortly after the port 36 has been completely opened, the valve commences to oscillate in the reverse direction, that is, the direction of the arrow 77, and the cycle of operations is repeated. The 85 mechanical power generated by the turbine is transmitted and taken off by means of a coupling 80, which is keyed to the end of the shaft 6.

It is apparent from a study of the above 90 cycle of operations that the speed of the turbine does not depend solely upon either the air pressure of the tank, the richness of the mixture, or the rate of oscillation of the shaft 12^a. If the power requirements, that is, the load upon the turbine, increase, the speed of rotation at once commences to drop, but the air-motor 26 still keeps on running at the same speed as before, since it is supplied with air at constant pressure 95 from the tank 1. The detonating chamber always receives a full and complete charge of explosive mixture just so long as the valve is reciprocating at a speed below 100 which wire-drawing occurs, and thus it is 105 obvious that a single adjustment of the proportion of gasoline and air will suffice for all conditions of load and speed of the turbine, the regulation of which for varying loads and speeds is accomplished by operating the regulating valve 27, and thus increasing or decreasing the rate of oscillation and consequent frequency of the explosions. If for any reason the turbine is stalled by 110 reason of excessive load, the leakage past the 115 buckets on the impeller disks may be insufficient to carry off the exploded mixture, and the detonating chamber may possibly become choked with burning gases at high temperature and pressure. However, nothing 120 is to be feared on this account, since back firing or escape of exhaust into the air tank is prevented by the use of the check valves 78 and 76 located in the air-inlet and mixture-inlet pipes, respectively. An even pressure is maintained in the tank 1 by running the air pumps at a suitable speed to supply 125 enough air for the turbine when the latter is running at its slowest speed, and when the explosions are of maximum frequency; ex- 130

cess of pressure in the tank at other times being taken care of by equipping the latter with a safety valve, not shown.

Since the active buckets on each disk occupy rather less than ninety degrees of arc, it is possible to equip the turbine with several detonating chambers and associated apparatus. It is also obvious that, instead of gasolene, any suitable liquid or gaseous fuel may be employed by slightly changing minor details connected with the fuel inlet. In any case, I do not wish to be limited by the details of construction shown except as specified in the appended claims.

15 I claim:

1. In an internal combustion engine, the combination of a wheel-casing, a turbine-wheel within said casing, means for at intervals igniting a charge of explosive fluid and then admitting the exploded mixture to the turbine-wheel when ignition is complete, and means for varying the length of said intervals independently of the speed of the turbine-wheel.

25 2. In an internal combustion engine, the combination of a wheel-casing, a turbine-wheel within said casing, an explosion chamber, means for at intervals admitting an explosive mixture to said chamber, means for igniting the mixture, means for connecting said chamber with the turbine-wheel after ignition has been effected, and means for varying the length of the intervals between the admission of said charges to the turbine-wheel.

30 3. In an internal combustion engine, the combination of a wheel-casing, a turbine-wheel within said casing, an explosion chamber, means for at intervals admitting an explosive mixture to said chamber, means for igniting the mixture, means for connecting said chamber with the turbine-wheel after ignition has been effected, and means for varying the length of the intervals between 45 the admission of said charges to the turbine-wheel independently of the rotative speed of the wheel.

40 4. In a gas turbine, the combination of a turbine-wheel, a stationary casing for said wheel, a stationary combustion chamber associated with said turbine-casing and having an inlet port connected to the fuel supply and an outlet port connected with the turbine, a valve arranged to open and close 55 said ports, and means for actuating said valve to place the chamber alternately in operative communication with the outlet and the inlet ports.

5. In a gas turbine, the combination of a 60 turbine-wheel, a casing for said wheel, a stationary cylindrical casing provided with an inlet port and an outlet port communicating with said turbine, a rotary valve within said casing adapted to open and close 65 said inlet and outlet ports, and means for

actuating said valve to effect communication between the chamber and the outlet and inlet ports alternately.

6. In a gas turbine, the combination of a turbine-wheel, a casing for said wheel, a stationary cylinder provided with an intake port for the admission of an explosive mixture to said cylinder, and an outlet port communicating with the turbine-wheel, a revoluble valve mounted within said combustion chamber and adapted alternately to open and close said intake and outlet ports, and means for igniting said explosive mixture.

7. In a gas turbine, the combination of a turbine-wheel, a casing for said wheel, a stationary cylinder provided with an intake port for the admission of an explosive mixture to said cylinder, an outlet port communicating with the turbine-wheel, a revoluble valve mounted within said combustion chamber and adapted alternately to open and close said intake and outlet ports, means for igniting said explosive mixture, and means for regulating the speed of rotation of said valve independently of the speed of rotation of said turbine.

8. In a gas turbine, the combination of a turbine-wheel, a casing for said wheel, a stationary cylinder provided with an intake port for the admission of an explosive mixture to said cylinder, an outlet port communicating with the turbine wheel, an oscillating valve mounted within said combustion chamber and adapted alternately to open and close said intake and outlet ports, means for igniting said explosive mixture, and means for regulating the speed of rotation of said valve independently of the speed of rotation of said turbine.

9. In a gas turbine, the combination of a wheel and its casing, a combustion chamber provided with an outlet to the wheel, valve mechanism controlling said outlet, a motor for actuating said valve mechanism, and means for firing an explosive mixture in the combustion chamber while the outlet port is closed, the valve mechanism being arranged to open said outlet after a sufficient time has elapsed to complete ignition and enable the exploded mixture to attain its maximum pressure.

10. In a gas turbine, the combination of a turbine-wheel and its casing, a combustion chamber, an independently driven valve-actuating motor, means for firing an explosive mixture in the combustion chamber while the outlet is closed, and valve mechanism operated by the motor for controlling said outlet port and suddenly admitting the charge to the turbine-wheel.

11. In a gas turbine, the combination of a turbine-wheel and its casing, a combustion chamber provided with a fuel-inlet and an outlet port, valve mechanism controlling

6
said ports, an independent motor for operating said valve mechanism, the valve mechanism being properly timed so as to admit the completely exploded charge to the turbine-wheel when at its maximum pressure, the turbine-wheel receiving the direct impact of the exploded mixture.

5 12. In a gas turbine, the combination of an air receiver, a fuel reservoir, a turbine-wheel and its casing, an air-pump driven by the turbine for maintaining pressure for charging the air receiver, a combustion chamber provided with an air inlet, a fuel inlet and an outlet port, valve mechanism 10 controlling said ports, and an air motor for driving said valve mechanism independently of the turbine.

13. In a gas turbine, the combination of a turbine-wheel and its casing, an air receiver,

a pump for charging said air receiver, a 20 cylindrical combustion chamber provided with a fuel-inlet port, an air-inlet port, and an outlet port communicating with the turbine-wheel, a rotary valve mounted within said combustion chamber and controlling 25 said ports, a motor for actuating said valve driven independently of the turbine, and means for igniting a charge of explosive mixture within said chamber, the valve mechanism being arranged to open the outlet port after ignition has been completed 30 and when the charge has reached its maximum pressure.

GEORGE ERLINGER.
